(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof when the right side view is a mirror image;

FIG. 5 is a top plan view thereof;

FIG. 6 is a bottom plan view thereof;

FIG. 7 is a rear perspective view thereof; and,

FIG. 8 is front view thereof, showing the lower main body separated from the upper body.

The dot dash broken lines in FIG. 8 indicate the path along which the lower main body is separated from the upper main body and form no part of the claimed design. The evenly spaced broken lines are directed to environment; the broken lines form no part of the claimed design.

1 Claim, 7 Drawing Sheets
